US00D783833S

(12) **United States Design Patent** (10) **Patent No.:** **US D783,833 S**
(45) **Date of Patent:** **** Apr. 11, 2017**

(54) **DEVICE FOR HOLDING SMALL PARTS**(71) Applicant: **WONG TECHNOLOGY LLC**,
Federal Heights, CO (US)(72) Inventor: **Alan Wong**, Westminster, CO (US)(73) Assignee: **Wong Technology LLC**, Federal
Heights, CO (US)(***) Term: **15 Years**(21) Appl. No.: **29/560,870**(22) Filed: **Apr. 11, 2016****Related U.S. Application Data**(63) Continuation of application No. 14/151,976, filed on
Jan. 10, 2014, now Pat. No. 9,314,315.(51) **LOC (10) Cl.** **24-01**(52) **U.S. Cl.**USPC ..... **D24/176**(58) **Field of Classification Search**USPC D24/176-186, 227, 229; D9/425;
